UNITED STATES PATENT OFFICE.

JAMES B. ADAMS, OF CHEAT NECK, WEST VIRGINIA.

VENDING MACHINE.

Application filed February 2, 1923. Serial No. 616,560.

To all whom it may concern:

Be it known that I, JAMES B. ADAMS, a native citizen of the United States, residing at Cheat Neck, in the county of Monongalia and State of West Virginia, have invented new and useful Improvements in Vending Machines, of which the following is a specification.

This invention relates to a vending machine which is mainly designed for vending stamps.

The present invention is an improvement over that shown in the patent granted to me on March 31, 1914, No. 1,092,125. The object of the present invention is to simplify the construction and operation of the patented device and to so arrange the parts that the size of the device can be reduced.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the invention.

Figure 2 is a horizontal sectional view.

Figure 3 is a section on line 3—3 of Figure 2.

Figure 4 is a section on line 4—4 of Figure 2 with some of the parts omitted.

Figure 5 is a view of the casing 15 and the parts associated therewith.

In these views 1 indicates a casing which is provided with a removable cover 2 and which has a discharge aperture 4 in one end thereof which opens into a trough 5. A supporting frame 6 is arranged in the casing and said frame supports a reel 7 for containing a strip of stamps, the feeding rollers 8 and 8' and the guide roller 9. The frame also carries a guide 10 for guiding the stamps to a discharge hole 11 which communicates with the aperture 4. The rollers 8 and 8' are provided with the intermeshing gears 12 and the shaft 13 of the lower roller is extended to receive a pair of ratchet wheels 14 and 14', one of which is located in a case 15 which is rotatably mounted on said shaft and which carries a spring pressed dog 16 for engaging the ratchet wheel 14.

A hand lever 17 is pivotally connected with one end of the casing and said lever is connected to the front part of the case 15 by means of the pin 18 which passes through a slot 19 formed in the said front end of the case. Thus when the lever is depressed the case will be rocked about the shaft 13 so as to cause the dog 16 to engage the ratchet wheel 14 and thus move the shaft and both feed rollers through their gear connections. Thus the strip of stamps will be fed forwardly from the wheel through the guide 10. A knife 20 is arranged for cutting the stamps as they leave the guide and said knife is connected by the slotted link 21 with the front end of the case 15 so that said knife will be operated as the case is rocked about its pivot which is formed by the shaft 13. A lever 22 is pivoted to the frame and has its toothed head 23 engaging the ratchet wheel 14' in such a manner that the movement of the rollers will be prevented as long as the head is in engagement with said ratchet wheel. The tail end of the lever 22 extends under the lower part of a coin chute 24 so that when a coin is deposited in the chute it will strike the end of said lever and thus raise the head of the lever out of engagement with the ratchet wheel to permit the parts to be rotated. A projection 25 on the case 15 limits the movement of said lever 22 so as to prevent the coin from dropping below said lever until the said case 15 has been moved to release the head 23 from the projection. After this takes place the lever 22 can move upwardly a distance sufficient to permit the coin to pass by it so that the lever can assume its normal position. By this time, however, the parts have been moved a sufficient degree to cause the knife to sever the stamp from the strip and to deposit the severed stamp in the trough. The rear end of the case 15 is extended and carries a projection 26 which acts to hold the end of the lever 22 down when the coin device is not to be used. When this lever is not to be used, it is pressed down and placed under the projection 26 which will hold it in a position with its head 23 out of engagement with the ratchet wheel and thus permit movement of the feed rolls without the insertion of the coin.

In order to permit the lever 22 to be placed in engagement with the projection 26, the rear end of said lever is pivotally connected with the main part, as shown at

22' so that it can be swung in a horizontal plane.

It is thought from the foregoing description that the advantages and novel features 5 of my invention will be readily apparent.

I desire it to be understood that I may make changes in the construction and in the combination and arrangement of the several parts, provided that such changes 10 fall within the scope of the appended claims.

What I claim is:—

1. A vending machine comprising a carrying reel, feeding rollers for feeding a 15 strip therefrom, intermeshing gears connected with the rollers, a pair of ratchet wheels connected with the shaft of one roller, a rocking member on said shaft, a dog carried thereby engaging one of the 20 ratchet wheels, a pivoted lever having a toothed part engaging the other ratchet wheel, said lever being adapted to be tilted by a coin, a projection on the rocking member for limiting the tilting movement of the

lever until said rocking member has been 25 moved to a certain position and a hand lever for rocking said member.

2. A vending machine comprising a carrying reel, feeding rollers for feeding a strip therefrom, intermeshing gears connected with the rollers, a pair of ratchet wheels connected with the shaft of one roller, a rocking member on said shaft, a dog carried thereby engaging one of the ratchet wheels, a pivoted lever having a 30 toothed part engaging the other ratchet wheel, said lever being adapted to be tilted by a coin, a projection on the rocking member for limiting the tilting movement of the lever until said rocking member has been 35 moved to a certain position, a hand lever for rocking said member, a knife for severing the parts from the strip and means for actuating the knife by the movement of the rocking member.

In testimony whereof I affix my signature.

JAMES B. ADAMS.
